UNITED STATES PATENT OFFICE.

HENRY W. BEESTON, OF PHILADELPHIA, PENNSYLVANIA.

DESIGN FOR AN UMBRELLA-STAND.

SPECIFICATION forming part of Design No. 19,409, dated November 12, 1889.

Application filed September 30, 1889. Serial No. 325,577. Term of patent 3½ years.

To all whom it may concern:

Be it known that I, HENRY W. BEESTON, a citizen of the United States, residing at Philadelphia, in the county of Philadelphia and State of Pennsylvania, have invented and produced a new and original Design for Umbrella-Stands, of which the following is a specification, reference being had to the accompanying drawing, forming part thereof.

10 My invention has relation to umbrella-stands of a new and original design, which will render the same ornamental and attractive; and it consists of an umbrella-stand, said stand being provided with a suitable top 15 and base of any desired pattern, and the main portion or body of the stand between said top and bottom, which is cylindrical, has a number of equidistant ribs or ridges extending all in the same direction spirally 20 around said body, the spaces between said ridges or ribs being depressed or concaved.

In the drawing, the figure is an elevation of an umbrella-stand embodying my design, and A represents the main portion or body of 25 the stand secured to the flaring top B at b

and to the base or bottom C at c. Said body is provided with the curved ridges or ribs a, extending from top to bottom spirally around said body, while the spaces a' between said ridges are depressed or concaved and are all 30 of the same width, owing to the fact of the ridges or ribs being equidistant from each other.

Having fully described my design, what I claim, and desire to secure by Letters Patent, 35 is—

The design for umbrella-stands, consisting of the cylindrical body A, provided with a top and a base or bottom, and having the spiral ridges or ribs a and the intermediate depressed or concaved spaces a', substantially 40 as shown and described.

In testimony that I claim the foregoing I have hereunto set my hand this 27th day of September, A. D. 1889.

HENRY W. BEESTON.
